UNITED STATES PATENT OFFICE.

CONRAD DIESEL, OF CHICAGO, ILLINOIS, ASSIGNOR TO FRANK DIESEL,
OF CHICAGO, ILLINOIS.

TIN CAN.

SPECIFICATION forming part of Letters Patent No. 751,784, dated February 9, 1904.

Application filed December 7, 1903. Serial No. 184,102. (No model.)

all whom it may concern:

Be it known that I, CONRAD DIESEL, a citizen of the United States, and a resident of Chicago, county of Cook, and State of Illinois, have invented certain new and useful Improvements in Tin Cans, of which the following is a specification and which are illustrated in the accompanying drawings, forming a part thereof.

10 The invention relates to that class of tin cans in which a flat seat is provided for the cover and the latter is soldered thereto so that it may be removed by a key, this class of cans being commonly known as "roll-top" cans, because the cover is rolled about the key in the operation of removing it.

15 The object of the invention is to improve upon the can forming the subject of the application for Letters Patent, Serial No. 176,905, of Henry E. Bandlow, in which the upper end of the can-body is provided with an outstanding flange, which returns upon itself and forms a seat for the cover, the return portion of the flange projecting inwardly beyond the wall of the can-body.

20 In the present invention all of the advantages found in the Bandlow can are retained, while the objectionable overlapping of the inner wall of the can-body by the return portion of the flange is overcome, and hence the contents of the package may be discharged, after the cover has been removed, without mutilation.

25 The invention consists in offsetting outwardly the body of the can at its upper end and forming an outstanding flange from the top of the offset, the flange being returned upon itself and the return portion projecting beyond the outstanding portion, but not projecting beyond the plane of the inner face of the can-body. This offset may take any desired form, several being shown in the accompanying drawings, illustrating the invention, in which—

30 Figure 1 is a side elevation of the can, partly in section, and Figs. 2, 3, 4, and 5 are sectional details of the joint, showing various forms.

The can-body 10 may be of any desired

shape. A round can is shown; but the invention is equally applicable to angular forms. 50 As the bottom of the can may be secured in any desired manner, I have not deemed it necessary to illustrate any form of joint therefor.

The upper edge of the can-body is offset outwardly, and this offset may take any of the several forms shown in Figs. 2, 3, 4, and 5.

55 In Fig. 2 the offset 11 is shown as substantially two right angles, the can-body being bent outwardly and at the outer end of the shoulder thus formed being bent upwardly. 60

In Fig. 3 the offset takes the form of an outward curve, as shown at 12.

65 In Fig. 4 the offset 13 is shown as a mere outward flaring of the can-body without curvature, and in Fig. 5 the offset 14 takes the form of a quarter circle or one-half of an ordinary beading. From the upper end of this offset, whichever form may be used, the metal is turned outwardly, as shown at 15, and then bent back upon itself, as shown at 16, thereby 70 forming a flat outstanding flange or seat for the cover. The inner edge of the return portion of this flange projects beyond the juncture of the offset and the outstanding portion 15 of the flange, as shown at 17, but does not 75 pass beyond the plane of the inner face of the side wall of the can-body.

76 The cover 18 is seated upon the return portion 16 of the outstanding flange and is secured thereto by the use of solder. The cover is 80 provided with an outstanding lug 19, to which a key may be applied for the purpose of rupturing the joint by rolling back the cover.

85 The construction described and illustrated, whichever form of offset may be employed, provides a recess at the top of the can-body, of which the overlapping end 17 of the return portion 16 of the flange is the top wall, so that outward pressure is applied thereto, thus relieving the strain upon the soldered joint and 90 greatly lessening and practically wholly overcoming the danger of rupturing the joint. Inasmuch, however, as this instanding ledge does not project beyond the inner face of the wall of the can-body it forms no obstacle whatever to the discharge of the contents of the 95

can, and the same may therefore be removed, if in solid form, entirely without mutilation.

I claim as my invention—

1. A can-body having its upper edge outwardly offset and flanged outwardly from the top of the offset, the flange being returned upon itself and the return portion overhanging the outstanding portion but not projecting beyond the plane of the inner surface of the side wall of the can-body.
2. A can-body having its end flared outwardly and provided at the upper end of the flaring portion with an outstanding flange which returns upon itself, forming a cover-seat, the inner edge of the return portion of

the flange projecting over the flaring portion of the can-body but not beyond the plane of the inner surface of the body-wall.

3. A can-body having its end curved outwardly and provided with an outstanding flange at the outer end of the curved portion, such flange returning upon itself to form a cover-seat and the inner edge thereof projecting beyond the outer end of the curve but not beyond its inner end.

CONRAD DIESEL.
